[57] ABSTRACT

This invention relates to a retractable spike, particularly for a golf shoe and the like, whereby the spikes can be either protruded or retracted from the bottom sole of the shoe to protect the floor of a clubhouse or the turf on the green. This movement of the spikes can be accomplished from the outside of the shoe by a mere rotation of a protruding knob.

RETRACTABLE SPIKE GOLF SHOE

An object of my invention is to provide a novel retracting spike means which can be readily actuated by the user upon rotation of a protruding knob at the heel of the shoe. The protruding knob rotates a cam shaft journaled in a recess in the sole of the shoe.

Another object of my invention is to provide a cam shaft which is flexible to permit flexing of the foot of the user, thus providing a more comfortable shoe.

Still another object is to provide a retractable spike structure for a golf shoe which is simple in construction and inexpensive to manufacture.

Other objects, advantages and features of invention may appear from the accompanying drawing, the subjoined detailed description and the appended claims.

In the drawings:

FIG. 1 is a perspective view of a golf shoe embodying my invention.

FIG. 2 is a sectional view taken on line 2—2 of FIG. 1.

FIG. 3 is a sectional view taken on line 3—3 of FIG. 2.

FIG. 4 is a view similar to FIG. 3 but showing the spikes in retracted position.

FIG. 5 is a fragmentary sectional view taken on line 5—5 of FIG. 3.

Referring more particularly to the drawing, the numeral 1 indicates a golf shoe which includes the usual sole 2 which is the usual shape, although somewhat thicker than commonly employed and includes the customary parts of a sole, as will be subsequently described. The sole 2 includes an inner lining 3 and an outer layer 4 which is spaced from the inner lining 3 to provide a space 5 in which the operating mechanism is placed, as will be subsequently described. A cam shaft 6 extends longitudinally through the space 5 and this cam shaft is journaled in a bearing 7 at the toe of the shoe, and a bearing 8 at the rear of the shoe. A flexible sleeve 9 is provided at the instep of the shoe 1 and is fixedly mounted in the shaft 6, but allows flexing of the shaft to permit flexing of the shoe while the user is walking. A knob 10 is provided at the rear end of the shaft 6 and protrudes from the heel of the shoe so that the cam shaft 6 may be manually rotated by the user to extend and retract the spikes, as will be subsequently described.

A spike plate 11 is positioned in the space 5 and extends from approximately the instep of the shoe to the toe. A plurality of spikes 12 extend from the plate 11 and project through aligned holes 13 when the spikes are extended. A plurality of straps 14 are attached to the upper surface of the plate 11 and extend over the cam shaft 6 and engage the cam shaft so that the plate 11 and the spikes 12 thereon may be moved vertically within the space 5 to extend or retract the spikes 12.

A heel plate 15 is positioned in the space 5 and at the heel of the shoe, and this heel plate carries a plurality of spikes 16 which protrude downwardly and project through appropriate holes 17 in the heel when the spikes are in use. An operating strap 18 is provided on the heel plate 15 and loops over the cam shaft 6 so that the heel plate 16 will be raised and lowered vertically as the cam shaft 6 is manually rotated. This causes the heel spikes 16 to raise or lower as required by the user.

IN OPERATION

The user rotates the knob 10 to, in turn, rotate the cam shaft 6, which will raise or lower the plates 11 and 15 simultaneously to extend or retract the spikes 12 and 16, as required by the user.

Having described my invention, I claim:

1. A retractable spike for a golf shoe comprising a sole on said shoe, a liner in said shoe spaced from the sole to form a space in the shoe above said sole, spike mounting means in said space, and spikes protruding from said mounting means, said sole having holes therein through which said spikes protrude in one position of the parts, and manually operable means connected to said mounting means to actuate said mounting means and motivate said spikes to protrude and retract said spikes, said spike mounting means comprising a plate, said plate being reciprocally mounted in said space.

2. A retractable spike for a golf shoe comprising a sole on said shoe, a liner in said shoe spaced from the sole to form a space in the shoe above said sole, spike mounting means in said space, and spikes protruding from said mounting means, said sole having holes therein through which said spikes protrude in one position of the parts, and manually operable means connected to said mounting means to actuate said mounting means and motivate said spikes to protrude and retract said spikes, said manually operable means comprising a cam shaft extending into said space.

3. A retractable spike for a golf shoe comprising a sole on said shoe, a liner in said shoe spaced from the sole to form a space in the shoe above said sole, spike mounting means in said space, and spikes protruding from said mounting means, said sole having holes therein through which said spikes protrude in one position of the parts, and manually operable means connected to said mounting means to actuate said mounting means and motivate said spikes to protrude and retract said spikes, said spike mounting means comprising a plate, said plate being reciprocally mounted in said space, said manually operable means comprising a cam shaft extending into said space, and a strap on the plate engaged by the cam shaft.
